(57) **CLAIM**

The ornamental design for a bottle with cap, as shown and described.

DESCRIPTION

FIG. 1 is a front and side perspective view of a bottle with cap;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

(Continued)

The broken line showing of a portion of the bottle with cap is included for the purpose of illustrating portions of the article and forms no part of the claimed design.
